CLAIM

The ornamental design for a docking station, as shown and described.

DESCRIPTION

FIG. 1 is a top front perspective view of a docking station showing our new design;

FIG. 2 is a bottom front perspective view thereof;

FIG. 3 is a top rear perspective view thereof;

FIG. 4 is a bottom rear perspective view thereof;

FIG. 5 is a top plan view thereof;

FIG. 6 is a bottom plan view thereof;

FIG. 7 is a front view thereof;

FIG. 8 is rear view thereof;

FIG. 9 is a side view thereof; and,

FIG. 10 is another side view thereof.

The shade lines in the Figures show contour and not surface ornamentation. The broken lines in the Figures show portions of the docking station which form no part of the claimed design. The dot-dash lines in the Figures show unclaimed boundaries.
